(57) **CLAIM**

The ornamental design for a spring form baking pan, as shown and described.

DESCRIPTION

FIG. 1 is a perspective view of the spring form baking pan; FIG. 2 is a front elevational view of the spring form baking pan;

FIG. 3 is a rear elevational view of the spring form baking pan;

FIG. 4 is a left side elevational view of the spring form baking pan;

FIG. 5 is a right side elevational view of the spring form baking pan;

FIG. 6 is a top plan view of the spring form baking pan; and, FIG. 7 is a bottom plan view of the spring form baking pan. The broken lines depicting hardware in the drawings form no part of the claimed design.
